UNITED STATES PATENT OFFICE.

FERDINAND LUDWIG CLAREN, OF LÜBECK, GERMANY, ASSIGNOR TO FIRM OF DRÄGER-WERK, HEINR. & ERNST. DRÄGER, OF LÜBECK, GERMANY.

BREATHING DEVICE.

1,177,383.

Specification of Letters Patent. Patented Mar. 28, 1916.

Application filed March 24, 1915. Serial No. 16,789.

To all whom it may concern:

Be it known that I, FERDINAND LUDWIG CLAREN, a subject of the German Emperor, and residing at Lübeck, in the German Empire, have invented certain new and useful Improvements in Breathing Devices, of which the following is a specification.

This invention relates to respiratory apparatus of the kind in which the mouth piece proper is kept in place by lugs held between the teeth. Such breathing devices have the disadvantage that the man carrying the apparatus is frequently only with great efforts able to hold the lugs tightly, 15 that often symptoms of cramp in the muscles of the jaw arise and that it is particularly difficult to secure an air tight closure of the device, which is of considerable importance because the entrance of poisonous gases into the respiratory organs is a great danger to the wearer of the apparatus. It even may happen that owing to some unexpected cause the mouth piece is pulled out of the mouth. These drawbacks 20 are avoided according to the present invention owing to the fact that the mouth piece proper is attached by the aid of a bandage constructed to conform to the outer contour of the lips in a similar manner to devices 25 which are applied to the upper lip for "training" mustaches and are known as "mustache trainees," by which means the mouth piece is readily applied and removed and securely held in the correct position 30 in use. It may be here stated that it has already been proposed to attach helmets or 35 nose and mouth coverings to the face of the user.

Figure 1 of the drawing shows a front 40 view of the device attached to the head and Fig. 2 is a side view of the same. Fig. 3 is a vertical section of the device. Fig. 4 is a side view of a modified construction and, Fig. 5 is a vertical section of another 45 modification.

The mouth piece connection comprises a tubular chamber *a* provided with a laterally extending pipe or breathing tube *b* to which a flexible rubber mouth piece *c* is secured so as to form an air tight connection therewith, but is easily removable therefrom for the purpose of renewing the mouth piece. The mouth piece consists of a strip *c*, preferably of soft rubber. It is

designed to fit between the underside of the lips and the teeth constituting a covering for the latter and forming an inner air tight connection between the chamber *a* and the mouth of the wearer. Small lugs *c'* are preferably formed on the inner face of the strip and project between the upper and lower teeth so that the strip may be held against displacement in the mouth.

As the strip is removable from the pipe *b* it is not designed as a carrier or support for the chamber. To provide such a carrier and to overcome the disadvantage of relying upon the teeth to support a mouth piece, as above described, I provide a suitable member which operates both as a support or carrier for the chamber, and as an auxiliary outer closure for the mouth operating to hold the inner closure in place. Said support is made in the form of a bandage *d* which closely surrounds the pipe *b* and is so secured to the chamber *a*, by shackles or straps *e*, that a space for the lips is formed between the outside of the strip *c* and the inside of the bandage which rests against the lips so as to hold them against the strip *c*. A perfect gas tight closure for the mouth is thus formed which will not only relieve the teeth from the strain caused by tightly gripping the lugs, but also relieves the operator of the effort of keeping the lips closed over the strip *c*.

The strips *f* of the bandage may be secured to a cap *g*, which surrounds the head like a helmet, by buckles or other attaching means. The strips *f* are provided with enlarged ends or thickened parts so as to prevent the ends slipping out when the buckles are loosened. The bandage may be made of any material that can be easily disinfected for instance of rubber or fabric impregnated with rubber, and is preferably made in one homogeneous piece.

The strips *f* of the bandage may be fastened to a skeleton head covering *g'*, Fig. 4. If so desired, the strips *f* may be made of such a length that they can be tied together on the back of the head or the neck or may be held there by buckles or the like.

In the construction shown in Figs. 1 to 3 it is assumed that the mouth piece *a* is so constructed that the breathing valves are mounted inside the same. This is however no feature of the invention itself. The

mouth piece may be formed of a simple tube Fig. 5 to which the branch pipe *b* is attached at an angle. In this case only one strap *e* can be used, a button *h* being attached to the mouth piece for fastening the bandage.

The device as described above has moreover the advantage that even persons who are not in the happy possession of all their teeth can use the apparatus without fear that the mouth does not close completely upon the mouth piece or that the lugs are bitten through, because the wearer of the apparatus can hold the rubber lugs projecting into the mouth by his teeth without pressure and is therefore not liable to cramp. The bandage effectively prevents any unintentional pulling out of the mouth piece.

20 I claim:

1. A mouth connection for a portable breathing apparatus, comprising a breathing tube, a flexible mouth piece removably connected thereto adapted to cover the teeth of an operator, and a bandage secured to the tube in front of the mouth piece adapted to conform to the outer contour of the lips of the operator.

2. A mouth connection for a portable breathing apparatus, comprising a breathing tube, a flexible mouth piece removably connected thereto adapted to cover the teeth of an operator, a bandage secured to the tube in front of the mouth piece and adapted to conform to the outer contour of the lips of the operator, and lugs on the inside of the mouth-piece for engagement by the teeth.

3. A mouth connection for a portable breathing apparatus, comprising a breathing tube, a flexible mouth piece mounted on the tube and adapted to cover the teeth, and a bandage arranged to engage the lips and

conform to the outer contour thereof to hold them in contact with the mouth piece.

4. A mouth connection for a portable breathing apparatus, comprising a breathing tube, a flexible mouth piece mounted on the tube and adapted to cover the teeth, a bandage arranged to engage the lips and conform to the outer contour thereof to hold them in contact with the mouth-piece, and means to connect the bandage to the head of the wearer.

5. A mouth connection for a portable breathing apparatus, comprising a chamber, a breathing tube extending therefrom, a flexible mouth piece removably connected to the tube and adapted to engage the teeth of the wearer, a bandage through which the tube projects, adapted to conform to the outer contour of the lips, and means connecting the bandage to the chamber in front of the mouth-piece so as to form a space for the lips between the mouth piece and bandage.

6. A mouth connection for a portable breathing apparatus, comprising a chamber, a breathing tube extending therefrom, a flexible mouth piece removably connected to the tube and adapted to engage the teeth of the wearer, a bandage through which the tube projects, adapted to conform to the outer contour of the lips, means connecting the bandage to the chamber in front of the mouth-piece so as to form a space for the lips between the mouth piece and bandage, and means on the bandage surrounding the head to press the bandage against the lips and thereby press the lips against the mouth piece.

FERDINAND LUDWIG CLAREN.
